LOCK

James Gorden Dunseath, Reno, Nev., assignor of
one-half to Harry Dunseath, Reno, Nev.

Application December 7, 1937, Serial No. 178,579

1 Claim. (Cl. 70—90)

The present invention relates to new and useful improvements in locks particularly for the sliding doors of show cases although it will be understood, of course, that the invention may 5 be used for any purpose for which it may be found adapted and desirable.

The primary object of the invention is to provide, in a manner as hereinafter set forth, a lock of the aforementioned character comprising 10 means for positively securing the show case doors in closed position, said lock further including what may be referred to as a key plug which is adapted to be removed when not in use.

Other objects of the invention are to provide a 15 lock of the character described which will be comparatively simple in construction, strong, durable, highly efficient and reliable in use, compact and which may be manufactured at low cost.

20 All of the foregoing and still further objects and advantages of the invention will become apparent from a study of the following specification, taken in connection with the accompanying drawing wherein like characters of reference designate corresponding parts throughout the several views, and wherein:

Figure 1 is a view in horizontal section through a portion of a show case equipped with a lock in accordance with the present invention.

30 Figure 2 is a view in front elevation, showing the plug in the barrel with the key removed.

Figure 3 is a view in rear elevation, showing the plug mounted in the barrel.

35 Figure 4 is a view in front elevation of the sleeve in the meeting rail of the innermost door which receives the pin on the plug.

Figure 5 is a view in rear elevation of the sleeve shown in Fig. 4.

40 Figure 6 is a view showing a portion of the outer meeting rail in side elevation and a portion of the inner meeting rail in vertical section with the lock in operative position therein.

Figure 7 is a view in front elevation of the barrel.

45 Figure 8 is an elevational view of the plug with the key therein, the tumblers being retracted.

Figure 9 is an elevational view of the plug with the key removed therefrom, the tumblers being 50 in projected position.

Figure 10 is an elevational view of the plug, looking at the inner end thereof.

Figure 11 is a cross sectional view through the outer end portion of the plug, taken substantially on the line 11—11 of Fig. 9.

Figure 12 is an elevational view of a portion of the key.

Referring now to the drawing in detail, it will be seen that the reference numeral 1 designates a portion of a show case comprising sliding doors 2 and 3. The doors 2 and 3 include inner and outer vertical meeting rails 4 and 5, respectively.

5 Mounted in the outer meeting rail 5 and extending therethrough is a metallic barrel 6. The outer end portion of the bore 7 of the barrel 6 is counterbored, as at 8. The reference numeral 9 designates diametrically opposite grooves which extend longitudinally in the bore 7 and which communicate with the counterbore 8. Fixed on the inner end of the barrel 6 is a metallic plate 10 which is recessed in the inner face of the meeting rail 5 and secured thereto by screws 11. The plate 10 has formed therein an opening 12 which is aligned with the bore 7 of the barrel 6 and into which flanges 13 extend, said flanges closing the inner ends of the grooves 9. This is shown to advantage in Figs. 3 and 7 of the drawing.

10 Mounted in the inner meeting rail 4 and extending therethrough is a metallic sleeve 14 which, when the doors 2 and 3 are in closed position, is aligned with the barrel 6. As best seen in Fig. 6 of the drawing, the outer end portion of the sleeve 14 is enlarged, as at 15.

15 Figure 12 is a view in front elevation of the barrel 6 for the reception of a removable key plug which is designated generally by the reference numeral 16. The plug 16 includes a metallic cylinder 17 which is insertable in the bore 7 of the barrel, said cylinder including a flange 18 on its outer end portion which is engageable in the counterbore 8 of said barrel.

20 The reference numeral 19 designates tumblers which are mounted in the cylinder 17. The tumblers 19 are retracted through the medium of a key 20 which is insertable in the cylinder 17 from the outer end thereof (see Fig. 8). The key 20 is releasably secured in the plug 16 through the medium of a spring pressed latch or 25 detent 21 (see Fig. 11) in the outer end portion of the cylinder 17 which is engageable in an opening 22 (see Fig. 12) which is provided therefor in said key 20.

30 Projecting from the inner end of the cylinder 17 is a neck 23 which terminates in a segmental head 24. The head 24 is engageable behind the flanges 13 when the doors 2 and 3 are locked, the 35 enlarged portion 15 of the sleeve 14 accommodating said head. Projecting from the head 24 is a pin 25 which is engageable in the sleeve 14.

40 It is thought that the manner of using the lock 45

will be readily apparent from a consideration of the foregoing. As hereinbefore stated, when the doors 2 and 3 of the show case 1 are in closed position, the barrel 6 and the sleeve 14 are aligned. 5 To retract the tumblers 19, the key 20 is inserted in the cylinder 17 of the plug 16. The plug 16, using the key 20 as a handle, is then inserted in the barrel 6 in such a position that the segmental head 24 thereon will pass between the flanges 13 and enter the enlarged portion 15 of the sleeve 14, the pin 25 entering said sleeve 14. The plug 16 is then rotated to the position shown in Fig. 3 of the drawing to prevent withdrawal of the segmental head 24 between the flanges 13 and bring 10 the tumblers 19 into registry with the grooves 9. The key 20 is then removed from the plug 16 and the tumblers 19 engage in the grooves 9 for securing said plug against rotation in the barrel 6. It will thus be seen that the plug 16 is secured 15 against both rotary and longitudinal movement in the barrel 6. With the pin 25 engaged in the sleeve 14 the doors 2 and 3 are, of course, locked together. The foregoing operation is substantially reversed to remove the plug 16 for unlocking 20 the doors 2 and 3. The latch or detent 21 secures the key 20 in the cylinder 17 sufficiently to permit said key to be used as a handle for withdrawing the plug 16 from the barrel 6.

It is believed that the many advantages of a

lock constructed in accordance with the present invention will be readily understood and although a preferred embodiment of the device is as illustrated and described, it is to be understood that changes in the details of construction may be resorted to which will fall within the scope of the invention as claimed. 5

What is claimed is:—

A lock for a pair of sliding doors, comprising a plate secured on one of said doors, a barrel fixed on said plate and extending through said one door, the plate having an opening therein aligned with the bore of the barrel, said bore of the barrel having longitudinal grooves therein, diametrically opposite flanges in the opening in the plate at one 15 end of the grooves, a removable plug insertable in the barrel and including a cylinder, a neck on one end of said cylinder, a substantially segmental head on said neck adapted to pass between the flanges and engageable therebehind upon rotation 20 of the cylinder for preventing withdrawal of said cylinder from the barrel, key operated tumblers mounted in the cylinder and engageable in the grooves for securing said cylinder against rotation in the barrel, and a pin projecting from the head 25 and engageable in the other door for securing the doors together.

JAMES GORDON DUNSEATH.
